United States Patent Office

Des. 183,780
Patented Oct. 21, 1958

183,780

TELEVISION RECEIVER

Richard J. Whipple, Abington, and Severin Jonassen,
Lafayette Hill, Pa., assignors to Philco Corporation,
Philadelphia, Pa., a corporation of Pennsylvania

Application November 19, 1957, Serial No. 48,550

Term of patent 14 years

(Cl. D56—4)

FIG. 2.

FIG. 1.

Figure 1 is a front perspective view of a television receiver, showing our new design; and

Figure 2 is a rear perspective view thereof.

The side of the television receiver not shown is substantially the same in appearance as the side shown.

We claim:

The ornamental design for a television receiver, substantially as shown and described.
